UNITED STATES PATENT OFFICE.

ELENA BUDNYK, OF VEGREVILLE, ALBERTA, CANADA.

COMBINED CHAIR AND LADDER.

1,348,474.

Specification of Letters Patent.

Patented Aug. 3, 1920.

Application filed January 4, 1918, Serial No. 210,279. Renewed February 7, 1920. Serial No. 357,016.

To all whom it may concern:

Be it known that I, ELENA BUDNYK, a subject of the King of England, residing at Vegreville, in the Province of Alberta and 5 Dominion of Canada, have invented certain new and useful Improvements in Combined Chairs and Ladders, of which the following is a specification.

This invention relates to folding chairs 10 and ladders and has special reference to a novel device whereby a ladder may be combined with a chair or removed therefrom so that the chair acts as a stand for the ladder. The invention also has reference to a novel 15 form of folding hinge or joints for the folding elements of chairs.

One important object of the invention is to improve and simplify the general construction of devices of this character.

20 A second important object of the invention is the provision of a means for connecting the ladder to the back of a chair.

A third important object of the invention is the provision of an improved hinge joint 25 for folding articles of furniture.

With the above and other objects in view, as will be hereinafter apparent the invention consists in general of certain novel details of construction and combinations of 30 parts hereinafter fully described, illustrated in the accompanying drawing, and specifically claimed.

In the accompanying drawing, like characters of reference indicate like parts in the 35 several views, and:—

Figure 1 is a side elevation of a folding chair showing the ladder attached thereto.

Fig. 2 is a rear view of the chair and ladder.

40 Fig. 3 is a section on the line 3—3 of Fig. 2.

In carrying out the objects of this invention there is provided a chair having the usual back 10. Extending from the side 45 members of the back 10 are lugs or eyes 11 which are arranged in pairs, the lugs of each pair being substantially opposite each other although in slightly staggered relation, which can best be seen in Fig. 2.

50 Through these lugs move plunger rods 12 having their inner portions overlapping. On the inner end of each plunger rod is formed an eye 13 which embraces the remaining plunger rod as can be clearly seen 55 by reference to Fig. 2. Surrounding the overlapping portions of the plunger rods

and between the eyes 13 is a coil compression spring 14 which bears at each end against a respective eye 13 so that the eyes are normally forced apart and thus the 60 plunger rods are drawn inward. The end of each plunger rod is bent at right angles as at 15 and carries a fork member 16 provided with a finger grip 17. The forks are inwardly directed toward each other and are 65 arranged to enter suitable openings in the side members of a ladder 18. By this means the ladder can be set up behind the chair and the forks entered in their openings so that the ladder will be held upright with 70 the chair forming a base as can be seen by reference to Fig. 1. It will also be obvious that the action of the spring 14 serves to hold the forks in position and thus prevent accidental detachment, of the ladder. The 75 chair 10 is provided with a seat 19 and a drop front 20 carrying legs 21. Lying on top of the chair seat 19 and projecting over the front edge is a hinge leaf 22, the remaining leaf of the hinge being indicated 80 as at 23 and being fixedly secured to the front 20 and leg 21. On the under side of the seat 19 beneath the hinge leaf 22 is fixed a hinge leaf 24, the remaining leaf of this second hinge being shown at 25 as secured 85 fixedly to the leg 21. Each of these hinge leaves is provided with a slot of peculiar character. The slot in the leaf 22 consists of an arcuate slot 26 terminating at each end in a hook 27. The slot in the leaf 24 consists of an arcuate central portion 28 terminating at one end in a hook 29 corresponding to the inner hook 27 and terminating at the other end in an enlarged hook-like opening 30. Extending through the seat is an 90 arcuate slot 31 registering with the slots 28 and 26 and terminating at its inner end in a hook portion 32 registering with the hook portion 29 and the inner hook portion 27. The outer end of this slot 31 above the opening 30 is enlarged as at 33 while the chair seat is recessed above the slot as at 34. At 35 is a movable pin provided on each end with a head 36 and this pin passes through the slots in the hinges and chair and is arranged to be moved from one end of the slot to the other. Fixed within the recess 34 is a pin 37 which is connected to the pin 35 by means of a coil tension spring 38. Now in folding the chair it is to be noted that the 100 bottom is connected to the back by means of a suitable hinge 39. Thereupon the upper 105

hinge leaf 22 will be free to move around its pivot point since the lower head of the pin 35 can pass through the openings 30 and 33. Thus, the seat may be folded up and the 5 front and legs folded upon such underside. In order to hold these parts in position there is provided an extra pair of lugs 40 similar to the lugs 11 and similarly equipped, the latter lugs being pivotally attached to the 10 seat 19.

There has thus been provided a simple and efficient device of the kind described and for the purpose specified.

It is obvious that many minor changes 15 may be made in the form and construction of the invention without departing from the material principles thereof. It is not therefore desired to confine the invention to the exact form herein shown and described but 20 it is wished to include all such as properly come within the scope claimed.

Having thus described the invention, what is claimed as new, is:—

1. The combination with a chair having a 25 back; of ears projecting from the back on opposite sides thereof, spring-pressed plungers extending through the ears and con-

stantly urged in opposite directions, and ladder side engaging elements carried by the outer ends of said plungers. 30

2. The combination with a chair having a back; of ears projecting from the back on opposite sides thereof, spring-pressed plungers extending through the ears and constantly urged in opposite directions, and 35 ladder side engaging forks carried by the outer ends of said plungers and adapted to enter holes in the sides of a ladder.

3. The combination with a chair having a back; of ears projecting from said back 40 rearwardly, plungers passing through said ears and having their inner portions overlapping an eye on the inner end of each plunger, a compression spring surrounding said plungers between said eyes and having 45 its ends engaging the confronting faces of the eyes and inwardly directed forks carried by the outer ends of the plungers and adapted to enter openings in the sides of a ladder.

In testimony whereof I affix my signature. 50
ELENA BUDNYK.
